WALL

Oscar L. Gent, Tulsa, Okla.

Application January 9, 1943, Serial No. 471,900

3 Claims. (Cl. 72—118)

My invention relates to the construction of walls and the like and more particularly to inner wall partitions and ceilings.

As is well known, composition insulating board is widely used in construction and is nailed or tacked into place. If large nails are used, then the construction is unsightly due to the exposed heads of the nails. And, nails mutilate the edges of the board. And, if small headed nails are used, the boards are even more likely to loosen and pull off of their supporting members. Expansion, contraction and vibration are factors which cause loosening of the boards.

My invention or system is applicable to either insulation boards with plain or interlocking edges. Or, it may be used with plaster board, or any product suitable for plastering, stucco or tile base. It eliminates the use of nails or screws as the fastening means.

Briefly, my invention comprises a penetrating unit which is forced into the board, a supporting clip having a spacing means carried by a furring strip and hardened plastic means surrounding these units to maintain them in place.

Also, another important feature of my invention lies in the fact that single clips support the entire wall, these clips being either pivotally or slidably mounted and both types being yieldable to give, in a sense, a free floating wall. Such type of wall is very desirable as it permits relative movement between the sheets of composition and their supporting structure.

Another feature of my invention is that not only are the exposed nail heads eliminated but the nails are done away with whereby the sheets of boards may be removed from a wall, if desired, and used in another construction, the sheets being just as easily applied the second time as initially, and their appearance in the wall being unmarred.

Another advantage of my invention is that it is relatively simple and cheap to install and yet the wall or unit produced is extremely sturdy and well-built and is in strict accordance with the several building codes and the like.

Also, the relative movement which is permitted to a limited degree between the parts of the wall, as previously mentioned, aids in the retardation of sound therethrough.

Still further objects, advantages and meritorious qualities reside in the special construction, combination and arrangement of the various elements forming the invention, as more fully hereinafter described and claimed, reference being

had to the accompanying drawings forming part hereof, wherein:

Fig. 1 is a perspective view of a ceiling structure supported in accordance with my invention.

Fig. 2 is a sectional view through one of the joists of Fig. 1 together with one of the several supporting units.

Fig. 3 is a view taken at right angles to Fig. 2.

Fig. 4 is a cross sectional view taken along the 10 plane of the line 4—4 of Fig. 2.

Fig. 5 is a view similar to Fig. 4, a modified form of penetrating means being shown.

Fig. 6 is a sectional view through the structure 15 illustrating the use of metal supporting or furring strips.

Fig. 7 is a side view of the clip for attaching furring strips to the wood supports.

Fig. 8 is an edge view of the clip of Fig. 7.

Fig. 9 is a view of the clip shown in Fig. 6 to 20 attach the furring strips onto the metal supports.

Fig. 10 is a view taken at right angles to Fig. 9.

Fig. 11 is a view of my supporting and spacing 25 clip.

Fig. 12 is a view of the penetrating means.

Like numerals refer to like parts throughout the several views.

Referring to Fig. 1, numeral 10 indicates a plurality of joists. These joists carry the furring strips and several sheets of composition boards positioned therebelow.

As is shown in Figs. 2 and 3, a nail 11 extends through the loop or eye part 12, see Figs. 7 and 8, of the clip 13. This clip 13 is bent laterally at 14, then downwardly at 15, and then again laterally at 16 to form a spring clamp of U-shape to receive a furring strip 20 or the like.

As is shown in Fig. 1, these strips 20 are spaced at suitable intervals and carry supporting and spacing clamps 21. As is shown in Fig. 11, the clip 21 has a top arm 22, a depending portion 23, an intermediate arm 24 extending substantially in parallelism to the top arm, another depending portion 25 and a terminal part 26.

As is shown in Figs. 2, 4, 5 and 6, the upper 45 arms of this clip 21 embrace or straddle the furring strip 20 and the lower part abuts against the rear face of the adjacent sheet of composition board, designated 30. Thus the sheets of board are maintained in spaced relationship to the several furring strips.

A penetrating means 31, see Fig. 12, has a body portion 32 with angularly extending ends 33 and 34, which may be pointed or sharpened as at 35 and 36, respectively, as by proper shearing of the wire or the like from which the clip may be made.

One of the clips 31 is inserted into the rear side of the plaster board or composition board closely adjacent to arm 26 of the spacer element or clip.

Now, the several surfaces around this joint are coated with a damp-proofing compound, as an 5 asphalt composition, as at 40.

A mixture of water, plaster of Paris, and pulverized glue forms a thick plaster similar in appearance to ordinary plaster and this is spread around and between the several parts as indicated 10 at 41.

These mixtures quickly harden and lock the several elements in place to thus form a joint which securely maintains the several parts together. As shown in Fig. 4, the asphalt composition is spread next to the furring strip and also upon the composition board and next the 15 plastic is spread around the joint as shown. It naturally fills all the spaces between the several parts and upon hardening acts in conjunction with the parts to provide an extremely rigid and sturdy joint which resists both compression and tension as well as any lateral movement which may occur.

Or, a combination of three ingredients, namely, 20 a liquid composed largely of asphalt, calcium sulphate (plaster of Paris) and pulverized glue may be made, this combination having the necessary qualities of adhesion, damp-proofing and hardness.

For example, there are a number of liquid damp-proofing products on the market, as R.I.W. 232, this name being registered in the Patent Office, or a similar liquid product is made by the Trus-Con Company. One gallon of this liquid asphalt may be mixed with one gallon of calcium sulphate and $\frac{1}{2}$ pound of pulverized glue. This makes an ideal mastic.

Thus, the clips 13 are first fastened to the supporting members, then the furring strips are inserted into the clips, spacer clips are placed at desired points, the mastic is then applied and the boards placed in position and adjusted. The members which penetrate the board have previously been inserted therewith.

Referring now to Fig. 5, this discloses a pair of small headed nails 50, these nails being forced into the rear of the board angularly as shown. These nails 50 replace the penetrating means 31 and thus anchor the several boards into place.

As shown in Fig. 5, 52 represents or indicates the mastic mixture which is a single mixture as just set forth. This mixture is applied to the several parts and hardens in a short time. This method of using only a single mixture is the preferred form of my invention as it simplifies the application of the boards.

Referring now to Figs. 6, 9 and 10, 55 indicates a clip having an upper U-shape for partly encircling the supporting strip 60, of channel shape as shown, and a lower U-shape at right angles to

the upper part of the clip, this lower part receiving the furring strips 20. Spacer or supporting clips 21 are located as shown and surrounded by the mastic 52 which acts to create a very strong juncture or joint.

From the above description it will be understood that the construction set forth is very sturdy and is extremely practical.

Various modifications may be made in the above described embodiments of my invention without departing from the spirit and scope thereof as defined in the following claims, it being understood that the words "wall" and "ceiling" wherever used are interchangeable and that the use of one or the other in the claims is not to be construed as a limitation to the use of the invention in a particular plane.

I claim:

1. A suspended wall structure or the like of the kind described, comprising, a plurality of sheets 20 of composition wall board, joists, furring strips, means for fastening the said furring strips to the joists, a plurality of pointed means forced into the rear face of the wall board adjacent to the several furring strips, each of said means having its inserted portion extending into the wall board at an angle for the purpose described, said means extending only partially through the wall board, damp-proofing and bond compound located around the non-inserted portion of the said pointed means upon the wall board, and plastic means, capable of hardening, located between the said pointed means and the adjacent furring strip.

2. In a wall construction of the class described, 35 a plurality of joists, furring, a plurality of insulation boards, means for fastening the furring onto the joists and a series of units for fastening the insulation boards onto the furring, each of said units comprising; pointed means for entering slantingly into the insulation board, yieldable spacing means located between the insulation board and the furring and adjacent the said pointed means, a moisture resistant coating upon the insulation board and the furring and plastic means located upon the two moisture-proofed and facing surfaces, said plastic means surrounding and covering parts of the said pointed means and the said spacing means and having the characteristic of hardening into a solid for the purpose 50 described.

3. In combination, a section of wall board, a furring strip therebehind, an elongated element forced angularly into but not through the wall board and extending adjacent to the furring strip, means attached onto the furring strip and extending adjacent to the elongated element, and plastic means between the wall board and the furring strip, said plastic means being located around the said elongated element.

OSCAR L. GENT.
